PUMP

Frank W. Ofeldt, McKeesport, Pa., assignor to
Homestead Valve Manufacturing Company,
Coraopolis, Pa., a corporation of Pennsylvania

Application June 29, 1936, Serial No. 87,847

12 Claims. (Cl. 103—227)

This invention relates generally to fluid pumps and more particularly to positive displacement reciprocating pumps and the method of operating the same.

5 The invention may be conveniently applied to installations for pumping fluids which by virtue of their viscous sticky nature would cause the valves of an ordinary pump to stick and become clogged and interfere with their proper operation. Again the pump may be conveniently employed for pumping fluids carrying insoluble substances in suspension which would prevent the proper seating of the valves of an ordinary displacement pump.

10 15 Displacement pumps generally employ poppet or ball check type intake valves which usually depend upon the suction pressure developed by the piston for their operation. The timing of suction operated valves is not dependable and materially reduces the capacity and the efficiency of the pump. Again the suction force developed by the pump is not sufficient to overcome the sticking action when pumping viscous or sticky fluids which cause the valves to adhere to their seats with a greater force than that developed by the suction of the pump.

I overcome these disadvantages by the provision of mechanical means for positively actuating the intake valve to lift it from its seat. This positive movement of the valve overcomes any adhesion forces created by the viscous or sticky fluid being pumped.

Again I provide means for positively actuating the intake valve to seat the same and do not rely upon the fluid pressure developed by the pump to close the valve.

The provision of these positive actions for operating the valves of a displacement pump increases the overall hydraulic efficiency of the pump, as the suction and fluid pressure developed by the pump are expended to act only on the fluid being pumped.

Again I am enabled to accurately time the operation of the valves and thereby avoid any loss in efficiency by forcing fluid back through the intake valve during the pressure period of the pumping cycle.

Another object of my invention is the provision of means for seating and unseating the valves of a displacement pump during the period of the highest speed of the movement of the valves. The operation of the valves in this manner is conducive to accurate timing which aids in increasing the pumping efficiency. Again I am enabled to produce or to prevent back flow

through the intake valves, which permits the use of a part or all of the full stroke of the pump piston to vary the displacement and hence the output. These results are not known to be attainable by cam operated valves of any previous displacement pump. The speed of the movement of the valve when seating, dislodges any insoluble substance from its seat which prolongs the usefulness of the valve without necessity of cleaning or refinishing the valve seating surfaces.

Another object of this invention is the provision of means for varying the capacity of a reciprocating displacement pump that is operated at constant speed.

Another object is the provision of a method for adjusting the seating of the valves in a displacement pump.

Another object is the provision of means for preventing foreign fluids and the fluid being pumped from being transmitted along the reciprocating piston to commingle with one another.

Another object is the provision of lubricating a reciprocating member and preventing leakage of the lubricant therefrom.

Another object is the provision of means for controlling the pressure of the delivery of the fluid being pumped.

Other objects and advantages appear hereinafter.

In the accompanying drawings wherein I have illustrated a practical embodiment of the principles of my invention:

Figure 1 is a vertical section of the pump comprising my invention taken along the line 1—1 of Fig. 2.

Fig. 2 is a horizontal section showing a triplex pump comprising my invention.

Fig. 3 is an end elevation of the pump showing the head block.

Fig. 4 is a sectional view taken along the line 4—4 of Fig. 1.

Fig. 5 is a plan view of the pump head block showing a modification thereof.

Fig. 6 is a side elevation of the pump head block shown in Fig. 5.

Fig. 7 is a sectional view taken along the line 7—7 of Fig. 5.

Referring to Figs. 1 to 4 of the drawings, 10 represents the pump casing enclosed at one end thereof by the cover 11. The sides of the casing are provided with the bearing assemblies 12 arranged to carry the drive shaft 13 which extends through walls of the casing. 14 represents oil

45

50

55

throwers which prevent the escape of oil past the cap plates. The outer ends of the drive shaft are arranged to be coupled with a suitable source of rotary power or other rotary device for driving the pump from either side or for driving another device through said shaft.

15 represents bosses on the exterior of the sides of the casing 10. Aligned holes are drilled in these bosses to receive the stationary crank shaft 10 16 which is pressed thereinto. 17 represents a crank shaft sleeve rotatably supported on the shaft 16 and having formed thereon the eccentric cranks 18, 19 and 20. The sleeve 17 is hollowed out within the eccentrics to form the lubricant 15 reservoirs 21. These reservoirs are fed by the passageways 22 extending to the exterior of the sleeve where they receive oil from the crank case by the splash system. The level of the oil within the crank case is indicated in Fig. 1.

20 23 represents thrust washers mounted on the opposite ends of the shaft 16 between the sides of the crank case and the ends of the crank shaft sleeve 17. It will be noted that clearance is provided between the sleeve 17 and the thrust washers 23, as indicated at the right in Fig. 2, to permit limited end play of the sleeve.

The end of the sleeve 17 adjacent the eccentric crank 20 is finished to receive the helical gear 24 which is secured to the sleeve, as by means 30 of the bolt 25 that passes through the gear and the eccentric 20 and is held in place by the lock washer and nut 26. The gear 24 is arranged to mesh with the helical pinion 27 formed on the drive shaft 13. The bottom of the casing is enlarged to receive the gear 24.

28 represents a plug on the top of the casing which may be removed for the introduction of oil. 29 represents the oil drain plug at the bottom of the casing.

40 30, 31 and 32 represent connecting rods, the crank shaft bearings of which form straps arranged to encompass the eccentrics 18, 19 and 20. The other ends of these connecting rods are pivotally secured to the crossheads 33, 34 and 35 45 by means of the wrist pins 36. Each of these cross heads are arranged to be reciprocated within their respective bores in the body of the pump casing.

The crossheads 33, 34 and 35 comprise a hollowed body portion 37 and concentric cylindrical extensions 38 of smaller diameter which extend through the bores in the body of the casing. These extensions are sealed within their respective bores by any suitable packing members 39 55 such as the cup washer type of oil seal. Thus the end of the body portion of each crosshead forms a pump piston for drawing and expelling oil through the passageways 31a in the head of the body portions 37 to lubricate the crossheads 60 as they reciprocate within their respective bores in the body of the pump casing.

The sides of the outer end of the casing body 10 are provided with the outwardly extending spacer abutments 40 upon which is mounted the 65 pump casing head 41. The casing head is secured to the pump body 18 by means of the stud bolts 42 held by the nuts 43.

44, 45 and 46 represent the pumping chambers in the head 41 arranged to receive the pump 70 pistons 47, 48, 49 respectively. The pump pistons are preferably of the same diameter and form an integral part of the crosshead extensions 38 but are separated therefrom by the cylindrical portions or necks 50 of reduced diameter.

75 As indicated in Fig. 1, the pump is arranged

to be mounted so that the pump pistons lie in a horizontal plane. In order to prevent the crank case oil from traveling along the surface of the extension 38 and the pump pistons to the pump packing and the pumping chambers, and also to prevent the fluid being pumped from traveling along the piston to the packing 39 and the crank case, I provide the pistons with the reduced sections 50. Any liquid traveling along the surface thereof would have to climb the radial shoulders 51, which form the reduced portion 50, in order to completely traverse the piston. The liquids will collect at the bottom of the radial shoulders 51 of the horizontal pistons and be thrown therefrom by inertia as the pistons are reciprocated. The liquids will thus drop from the pump casing to the floor without harming their opposite packings or polluting each other which may lead to destruction.

52 represents the packing chambers for the 20 pumping pistons 47, 48 and 49. These chambers are provided with the packing elements 53 held in place by the gland members 54.

The outer end of the pump head 41 is provided with the plugs 55 and 56 which are oppositely 25 disposed to the pumping pistons and the intake valves 57 respectively.

These intake valves are of the poppet type, having the head 58 and the stem 59 guided by the member 60. The head is arranged to seat on the 30 valve seat member 61.

62 represents an adjusting nut secured on the threaded end of the stem 59 by means of the lock nut 63. The nut 63 is arranged to support one end of the helical valve spring 64 which is 35 held at its other end by the cap member 65. The cap member 65 carries the packing 66 for sealing the valve stem 59 against outward leakage. Thus the spring 64 seats the valve and holds the packing 66 against the valve guide member 60 to automatically compensate for the wear of the packing.

The intake valves are operated by the tappets 67 which engage the adjusting nut 62 when reciprocated by the tappet lever or bell crank members 68 pivotally supported on the rod 69. 45 The rod 69 is held in the lugs 70 integral with the casing body 10 within the crank case. The ends of the tappets 67 are shaped to freely ride on the arcuate surface 71 of the lever or bell crank member 68 when the latter are oscillated. 50

The lever or bell crank members 68 are provided with the tail portions 72 arranged to engage and ride on the perimetral surface of the connecting rod straps 32 from whence the lever or bell crank members receive their oscillating 55 motion.

The contact point on the tail 72 of the lever or bell crank 68 is positioned in substantially ninety degrees phase relation from the center line of the pump piston with respect to the crank shaft 15. 60 The operating cycle of the lever or bell crank 68 is therefore ninety degrees out of phase with that of the pump piston. As shown in Fig. 1 of the drawings, the valve adjusting nut 62 is arranged so that the valve will commence to open as the 65 piston 49 commences its suction stroke and the strap of the connecting rod 32 moves the lever or bell crank tail 72 upwardly, assuming the pump to be disposed in a horizontal position. The valve 57 will be fully opened when the piston is half way down its stroke and the eccentric crank arm has moved through ninety degrees. From this point the valve 57 will begin to close and will be fully closed when the eccentric crank reaches the position of one hundred 75

and eighty degrees from that shown. During the pressure stroke of the pumping cycle the valve 57 remains seated and the lever or bell crank tail 72 may ride free on the strap 32.

- 5 When the valve 57 is fully opened the eccentric crank is vertical. Graphically this point may be indicated as the crest of a sine curve representing the valve operating cycle. The movement of the valve is therefore slowest at this point.
- 10 The fastest movement of the valve occurs at the instants that it is opened and closed, which may be represented graphically by the points of intersection of the sine curve with the base or zero line. The graphic representation of the inlet valve operating cycle with respect to time would then be a series of the positive halves of a sine curve, as the valve is not ordinarily operated during the other half of the cycle. Under these conditions the pump will operate at maximum capacity.

20 By positioning the valve adjusting nut 62 further up the stem than that shown in Fig. 1, the opening of the valve will be delayed and its closing will be hastened, thus reducing the time that the inlet valve 57 is open and consequently reducing the output capacity of the pump.

25 With this setting of the valve 57 the discharge of the pump starts, in point of time, after the beginning of the pump pressure stroke and continues to the end of the pump pressure stroke. The vacuum created during the first part of the pump suction stroke is sufficient to permit the flow of a volume of fluid, into the pump chamber, equal to that displaced by the pump piston when the inlet valve opens. This destroys the 30 vacuum formed during the first part of the suction stroke. The piston will continue to draw in fluid until the inlet valve closes. The piston then completes its suction stroke without drawing any more of the fluid into the pump chamber, which creates a vacuum during the last part of the suction stroke. During the pressure stroke the pump piston must move initially through the same displacement to destroy the vacuum and before any pressure will be developed in the 35 chamber to cause a discharge of fluid from the chamber. The displacement by the piston then continues until the end of the pressure stroke. By setting the inlet valve 57 in this manner the pump capacity may be reduced to only one-half 40 of its full displacement. This limitation is of course based upon the assumption that the operating speed of the pump and viscosity of the fluid are not contributing factors.

45 Likewise by screwing out the adjusting nut 62 from the position shown in Fig. 1 the closing of the valve 57 will be delayed to a time lagging the beginning of the pump pressure stroke and the opening of the valve 57 will be advanced to a time during the pump pressure stroke. The timing of the valve may be said to lead the pump suction stroke. Thus the discharge time of the pump occurs only when the intake valve is closed or during the middle portion of the pump pressure stroke. During the first and last parts of the pump pressure stroke the pump is displacing the fluid back through the open inlet valve 57.

50 The full capacity of the pump is obtained when the valve 57 opens and closes at the ends of the piston strokes. The capacity of the pump may be varied by changing the timing of the valve for pumping minute quantities of the fluid.

55 The outer end of the bores carrying the tappets 67 are enlarged as shown at 73 to form a recess for receiving the oil that is splashed on

the tappets within the crank case and carried therealong. This recess is connected by the passageways 74 to the bores in which the cross-head body portions 37 are reciprocated. The passageways 74 are arranged to be uncovered by 5 the portions 37 as they near the end of the inward stroke. The passageways 37a in the cross-heads are restricted and a sub-atmospheric pressure is developed in the lubricant pump chamber during the retracting period of the pumping 10 stroke. When the crosshead uncovers the port of the passageway 74 all the oil collected in the recess 73 around the tappets 67 is drawn through the passage 74 into the lubricant pumping chamber. This avoids any loss of oil from around 15 the tappets and dispenses with the necessity of packing them.

20 The pump head 41 is provided with the intake passageway 75 which extends transversely thereof and connects the valve ports back of the valve 25 seat members 61. This passageway may be connected to the system at either side of the pump as indicated by the pipe lines 76 and 77 in Fig. 3 or one side may be closed as indicated by the plug in dotted lines at 78. If all three pistons are employed to pump the same fluid the passageway 75 remains uninterrupted for its full length. However if fluids from different sources are to be pumped at the same time then the intake of one or more of the pumps may be 30 isolated. As a convenient means for accomplishing such isolation I provide the head with an internally threaded bore intersecting the passage 75 in which bore is mounted the screw plug valve 79 which may be screwed inwardly, 35 as by hand, to interrupt the passage. Thus as shown in Fig. 3 the left hand pump may be supplied with one fluid through the connecting pipe 76 while the other pumps may be supplied with another fluid through the pipes 77. Thus two 40 fluids may be simultaneously pumped as disclosed for instance in Letters Patent No. 1,855,866, issued April 26, 1932, and Letters Patent No. 1,925,643, issued September 5, 1933, and in my application for Letters Patent Serial No. 36,290, filed 45 August 15, 1935.

45 The exhaust valves of this pump may be constructed in any suitable manner, such for instance as the intake valves. However, for ordinary use the ball check type of valve when properly installed will perform satisfactorily. Thus 50 80 represents the outlet check valve balls arranged to be seated inwardly on the valve seating members 81 in the valve chambers 82, 83 and 84 positioned above the pump chambers 44, 45 and 46. Where such a position is inconvenient the ball valve may be provided with springs to normally maintain them on their seats.

55 These valve balls are preferably made from a hard alloy so as to resist wear and corrosion.

60 The outlet valve chambers are closed by the plugs or bonnets 85. These bonnets are also employed for setting the outlet valves and adjusting the lift thereof for high speed operation. This is accomplished by forcing the bonnet shoulder tight against the shoulder of the pump head. This force permits the inner end of the bonnet 85 to contact the ball valve 80, forcing it against its seat. The ball valves 80 being made of hard alloy will not be injured by this pressure. However the valve seat and the inner end of the bonnet 85 will be indented, as shown at 65 86, being of softer material where they have been contacted by the ball. The indenture in the end of the bonnet and the valve seat created by cold 70 75

flowing of the metal by this compressive force cold works the surface thereof, making it hard and less susceptible to wear. A shim washer or washers 87 having a thickness corresponding to 5 the desired lift of the ball valve is then placed between the bonnet and the pump head shoulders. By the removal of one of several shims that may be positioned under the bonnet I am enabled to compensate for any wear that may 10 occur on the valve structure and the inner end of the bonnet.

This method of seating and adjusting these ball check valves has been found to be accurate and successful in determining their lift. The 15 cold working of the metal of the seat and the inner end of the bonnets prolong the life of the valve. Obviously the method of setting a valve is not limited to ball valves.

88 represents the outlet passageway connecting 20 to the valve chambers 82, 83 and 84 for receiving the discharge from the three pump chambers. This passageway is connected to the outlet pipes 89 and 90 leading from opposite sides of the pump head. If only one outlet pipe is 25 necessary for connecting the pump to the system, one of the lead pipes may be replaced by the plug 91, as shown in dotted lines in Fig. 3.

A pump head of this type may be employed to 30 pump fluids from different sources and subsequently mix them in the discharge passageway 88.

Referring now to Figs. 5, 6 and 7 wherein I 35 have shown a modification of the pump head 41, 92 represents the inlet and 93 the outlet passageways for the pump chambers 45 and 46. 94 represents the inlet and 95 the outlet passageways for the pump chamber 44. Thus the triplex pump has been converted to a duplex pump and a 40 single pump in the same structure.

This displacement pump is provided with a 45 fixed stroke and when operating at a constant speed any change in the timing or setting of the inlet valve will change the quantity of the liquid displaced by the piston as described above. Thus the inlet valve setting controls the output of the 50 pump at a constant speed. When the output of the pump is connected to a closed system, which may be represented by the valve 96 in the discharge line 97, a pressure will be set up in the 55 system by the constant displacement of the pump operated at a constant speed. This displacement pressure depends upon the opening of the valve 96 which controls the quantity of fluid passing from the pump. To limit the pressure developed 60 in the system I provide a by-pass passageway 98 which in this instance connects the pump chamber 44 with the inlet passageway 94. The by-pass or escape orifice may be directed to the atmosphere or any other suitable place.

The passageway 98 is constructed to have a 65 predetermined aperture. The size of the aperture may be made fixed within the pump head casing as shown, or it may be regulated by means of a valve. However, at a constant pump speed the size of the aperture in combination with the displacement of the pump piston controls the amount of fluid that passes therethrough during the pressure stroke. If the valve 96 is closed 70 the pressure developed in the pump chamber will be a maximum, as the total discharge of the pump due to the piston displacement must pass through the by-pass 98. Again if the valve 96 is opened to permit some of the fluid to pass therethrough, then the pressure in the system will be lowered, 75 as there are two channels through which the fluid

discharged from the pump may pass. Thus it is obvious that when pumping against a certain head, with a constant displacement capacity pump operated at a constant speed, the effective head pressure will decrease, since a part of the 5 fluid is by-passed.

Thus by controlling the quantity of the liquid forced through the by-pass during the compression stroke at a constant operating speed I am 10 enabled to regulate the limiting pressure that will be developed within the pumping chamber and the system. By controlling the opening of the valve 96 the pressure in the system may be regulated within the limits created by the orifice and the other contributing factors. 15

By employing this by-pass on a displacement pump I may dispense with the ordinary pressure relief valve arranged to maintain a predetermined pressure within a system and to exhaust the pressure therein when it exceeds a maximum. 20 I am also enabled to dispense with the use of a regulator for maintaining a constant pressure within the system as the valve 96 measures the quantity of liquid leaving the system which in turn controls the pressure developed therein owing to the predetermined size of the passageway 98 and the adjustable feature of the valve 96. 25

There has long been a great need for a small pump to handle fluids at a relatively high pressure and at the same time in small quantities. 30 To fill the gap that exists between the mechanical lubricator type and the rotary centrifugal type I have developed the pump disclosed herein.

This pump has a wide application because of the low operating horse power required, the wide 35 range of pressure, and the positive displacement feature resulting in high volumetric efficiency. Pure water, water containing various percentages of alkaline compounds, fuel oils, mineral oils and various chemicals are most readily handled by 40 this pump. It is adaptable to a great variety of uses such as boiler feed, boiler compound injection, condensate returns, small hydraulic presses, fuel oil pumps for oil burners, pumping of chemicals, air conditioning apparatus and control apparatus. 45

I claim:

1. In a displacement pump, the combination with the pump chamber, a piston working therein and a poppet valve for the admission of fluid to 50 the chamber, of a single crank for reciprocating the piston and operating the valve, and means whereby the speed of movement of the valve is increased as it seats and unseats.

2. In a displacement pump, the combination 55 with the pump chamber, a piston working therein and a poppet valve for the admission of fluid to the chamber, of a single eccentric means for reciprocating the piston and operating the valve, said means being arranged to increase the speed 60 of movement of the valve in seating and unseating the same.

3. In a displacement pump, the combination with the pump chamber, a piston working therein and a poppet valve for the admission of fluid to 65 the chamber, of a single crank for reciprocating the piston and operating the valve, means whereby the speed of movement of the valve is increased as it seats and unseats, and means for adjusting the movement of the valve relative to that of the 70 piston.

4. In a displacement pump, the combination with the pump chamber, a piston working therein and a poppet valve for the admission of fluid to the chamber, of a single eccentric means for 75

- reciprocating the piston and operating the valve, said means being arranged to increase the speed of movement of the valve in seating and unseating the same, and means for adjusting the movement of the valve relative to that of the piston.
5. In combination with a pump chamber, a pump piston working therein, and inlet and outlet valves for the chamber, of a rotary crank connected to the piston to reciprocate the latter, and a pivoted bell crank one arm of which is swung directly by the first mentioned crank and the other arm of which is operatively connected to the inlet valve to cause the same to open and close in timed relation to the movement of the piston.
10. In combination with a pump chamber, a pump piston working therein, and inlet and outlet valves for the chamber, of a rotary crank connected to the piston to reciprocate the latter, a pivoted bell crank one arm of which is swung directly by the first mentioned crank and the other arm of which is operatively connected to the inlet valve to cause the same to open and close in timed relation to the movement of the piston, and means for regulating the timing of the opening and closing of the inlet valve.
15. 6. In combination with a pump chamber, a pump piston working therein, and inlet and outlet valves for the chamber, of a rotary crank connected to the piston to reciprocate the latter, a pivoted bell crank one arm of which is swung directly by the first mentioned crank and the other arm of which is operatively connected to the inlet valve to cause the same to open and close in timed relation to the movement of the piston, and means for regulating the timing of the opening and closing of the inlet valve.
20. 7. In combination with a pump chamber, a pump piston working therein, and inlet and outlet valves for the chamber, of a rotary crank connected to the piston to reciprocate the latter, a pivoted bell-crank lever one arm of which is swung directly by the first mentioned crank, and operative connection between the other arm of the bell crank and the inlet valve to cause the latter to open and close in timed relation to the movement of the piston and comprising means for regulating the timing of the opening and closing of the inlet valve.
25. 8. In combination with a pump chamber, a pump piston working in the chamber, and inlet and outlet valves for the chamber, of a rotary crank, a strap encircling the crank and operatively connected to the piston to reciprocate the latter, and a pivoted lever riding on the strap and operatively connected to the inlet valve to

cause the same to open and close in timed relation to the movements of the piston.

9. In combination with a pump chamber, a pump piston working therein, and inlet and outlet valves for the chamber, of a rotary crank, a strap encircling the crank and operatively connected to the piston to reciprocate the same, and a pivoted bell crank one arm of which rides on said strap and the other arm of which is operatively connected to the inlet valve to cause the same to open and close in timed relation to the movements of the piston.

10. In combination with a pump chamber, a pump piston working therein, and inlet and outlet valves for the chamber, of a rotary crank, a strap encircling the crank and operatively connected to the piston to reciprocate the same, a pivoted bell crank one arm of which rides on said strap and the other arm of which is operatively connected to the inlet valve to open the same in timed relation to the movements of the piston, and means for regulating the timing of the opening and closing of the inlet valve.

11. In combination with a pump chamber, a pump piston working therein, and inlet and outlet valves for the chamber, of a rotary crank, a strap encircling the crank and operatively connected to the piston to reciprocate the same, a pivoted bell crank one arm of which rides on the strap, and operative connection between the other arm of the bell crank and the inlet valve for opening the latter in timed relation to the movements of the piston and comprising means for regulating the timing of the opening and closing of the inlet valve.

12. In a displacement pump, the combination with the pump chamber, a piston working therein and a poppet valve for the admission of fluid to the chamber, of a single crank for reciprocating the piston and to operate the valve, means whereby the speed of the movement of the valve is increased as it seats and unseats, and means for varying the capacity of the pump independently of the speed of the operation of the pump.

FRANK W. OFELDT. 45
